UNITED STATES PATENT OFFICE.

JOHN H. ELWARD, OF ST. PAUL, MINNESOTA.

IMPROVEMENT IN HARVESTERS.

Specification forming part of Letters Patent No. **152,622**, dated June 30, 1874; application filed March 10, 1874.

To all whom it may concern:

Be it known that I, JOHN H. ELWARD, of St. Paul, county of Ramsey, State of Minnesota, have invented certain new and useful Improvements in Harvesting-Machines, of which the following is a full, clear, and exact description, reference being had to the accompanying drawings, making part of this specification, in which—

Figure 1 is a plan view of my improved harvester, broken away in part to more fully show the construction. Fig. 2 is a vertical transverse section on line $y y$, Fig. 1. Fig. 3 is a plan view of the binders' carriage, showing the manner in which it is connected with the machine or main frame. Fig. 4 represents an outer or stubble side elevation, with the binders' carriage removed and the elevator shown in broken section on line $z z$, Fig. 2; and Fig. 5 represents a vertical transverse section through the outer or grain side of the platform and platform-apron.

Similar letters of reference denote corresponding parts wherever used.

The invention consists, first, in a novel combination of stripper-belts with the platform and elevator aprons; second, in a novel construction of the elevator, whereby the elevator-apron can be made to move in either direction, and is adapted to elevate the grain by either its upper or lower face acting thereon, as the circumstances under which the grain is harvested may suggest or require, and as herein-after explained; and, lastly, the invention consists in certain details of construction and arrangements of parts, all as hereinafter fully set forth.

In the accompanying drawings, A represents the main drive-wheel; A', the outer platform-carrying wheel; B B¹ B², the main frame; C C¹, the elevator-frame; D D' the platform and elevator aprons, all of usual or any preferred construction. The bottom of the platform-frame, underneath the apron D, is tightly closed by a wood or sheet-metal bottom, d, and this bottom, in connection with the closed end at d¹, forms a receptacle for such grain as may be shattered or thrashed out in cutting and conveying the same to the inner end of the platform. At the outer end of the apron D (see Fig. 5) is placed a concave, d², conform-

ing in curvature, or nearly so, to the sweep of the teeth on the slats of apron D, and extending from the horizontal plane of the bottom board, d, to the vertical plane of the end or divider board, d¹, as shown, for enabling the teeth of the apron D to pick up and return any grain or straw that may fall between the divider-board and end of the apron, or otherwise get under said apron. With this construction the usual inclined overhanging divider-shield may be dispensed with, if desired. The elevator-bottom C² is slotted, as shown at c in Figs. 1 and 4, to permit the ends of the teeth on the elevator-slats to pass below its upper surface, on which the grain rests, and up which it is carried, in such manner as to avoid the objectionable frictional contact of the teeth with such upper surface usual to the close bottom of elevators of this class as heretofore constructed, while at the same time it insures the regular and even elevation and delivery of the grain. A box or receptacle, E, extending from front to rear of the elevator, is pivoted underneath the elevator-frame, in the transverse front and rear bars, B, of the frame, and serves to receive and retain such shattered or shelled grain as may escape through the slots c in the elevator-bottom. The platform may be provided, if desired, with a series of rods or wires, b, arranged over the apron D, connected at their outer ends with the end or divider board d¹, and at their inner ends with the elevator-bottom C², near its lower end, as shown in Figs. 1 and 2, said rods or wires forming a stationary platform, on which the grain falls as it is cut, and between which the rake-teeth of the apron D project for removing the grain; or the rods b may be dispensed with, and in lieu thereof a series of curved fingers, b', attached to the elevator-bottom C², at or near its lower end, or to other convenient support, and extending outward into suitable position to take the grain from the teeth of the slats of the apron D, as shown, the rods b or b', whichever may be employed, serving to strip the grain from the rake-teeth of apron D. At the inner end of the platform-apron, and in close proximity to the inner apron-roller, is arranged a horizontal shaft, upon which is placed a series of fast pulleys, F, and upon the opposite side of

or underneath the elevator-bottom C² is arranged another shaft, similarly provided with fast pulleys F¹, upon which are placed a number of stripper bands or belts, F², which pass through slots in the elevator-bottom, and are armed upon their outer faces with teeth f, which, when the belts are rotated in the same direction with the apron D, pass in close proximity to the inner end of said apron, or to the slats and teeth thereon, and serve to take the grain from the platform-apron and to convey it inward within reach of the elevator.

A similar arrangement of stripper-belts is made at the upper end of the elevator, to take the grain from said elevator and convey it to the desired point of discharge, G G' indicating the rollers or pulleys, and g the stripper-belts, the shafts of which are mounted in bearings in a frame, H, which has a horizontal pivotal connection, a h h, with the top of the elevator-frame, for permitting the stripper-belts to be set or adjusted to any desired angle of relation to the elevator-apron, and to vary the elevation at which the grain is discharged from the stripper-belts. The stripper-belts are made to move in the same direction with the aprons from which they take the grain, being operated by belts and pulleys, as shown in Fig. 1, or any other suitable or preferred arrangement of mechanism for the purpose; and when the grain is carried up by the elevator-apron acting underneath, the stripper-belts also act underneath, as indicated by the arrows in Fig. 2, and the grain is carried across a flooring, h', of the pivoted stripper-frame H to the desired point of discharge; but where, from any cause, such as a damp or sticky condition of the grain, it may be found desirable to carry the grain upward on the face of the moving apron D' itself, by simply crossing the belt which drives said apron, the direction of movement of both the elevator-apron and its stripping-belts g will be reversed, causing the grain to be carried upon their upper faces from the stripper-belts f to the point of discharge. Under this arrangement the grain is held down upon the upper inclined face of apron D' by yielding spring-rods i, secured at their lower ends to a cylindrical rod, I, which is suspended by springs j from the seat-plank J, which overhangs the apron D', being supported upon projecting bars J' in front and rear of said apron. The upper ends of the rods i are left free and overhang the upper end of the elevator-apron, as shown, said yielding rods serving to gently hold the grain to the face of the apron without materially resisting its progress until it is delivered to the stripper-belts. The supporting-rod I, which forms, as it were, a mouth-piece for straightening the grain and admitting it to the elevator by its cylindrical form, facilitates the admission of the grain, and offers the least possible resistance to its passage. The reel-shaft K, at its inner end, is mounted in a horizontal longitudinal bar, K', which is adjustably connected with the uprights C of the elevator-frame, a series of

holes, k k, and the fastening bolts or screws k¹ permitting the vertical adjustment of the bar K' and reel-shaft K, and a series of notches or bearings, k², or an adjustable sliding box, permitting the horizontal or backward and forward adjustment for adapting the reel to the condition of the grain.

A similar construction may be employed for adjusting the outer end of the reel-shaft. Guide-pulleys l l for guiding the reel-belt are mounted in a bell-crank arm, L, pivoted at its lower end to an upright or post, C, of the elevator-frame. The upper horizontal arm is provided with a curved slot, and connected with the post by a bolt or set-screw, which permits its adjustment forward or backward on the lower pivoted end for regulating the tension of the reel-belt. M, Figs. 1, 2, and 3, represents a binders' carriage, consisting of a rectangular frame, of any suitable construction, mounted upon wheels N, with its inner side, M, parallel with the outer or stubble side of the main frame, and connected therewith by links O O, pivoted at one end to the binders' carriage, and at the other to the main frame, one in front and the other in rear, as shown in Fig. 3, by horizontal pivots at right angles to each other, to accommodate the independent movements of the binders' carriage, while at the same time always holding said carriage in proper relation to the machine to receive the grain as it is discharged from the elevator. A drag-bar, P, pivoted at its forward end to the main frame, and at its rear end to the binders' carriage, serves to draw the carriage as the machine is drawn forward. The carriage has an upright frame supporting the bars Q, which form a seat or lateral support for the binders standing on the platform or flooring of the carriage M. Q' Q' are longitudinal bars, connected by a series of transverse rods or wires, q, upon which the grain is caught as it is discharged from the elevator. The frame of the binders' carriage may be closed, either in whole or in part, as at m m, upon its sides, to form a receptacle for shattered grain. The inner side board M' extends upward the height of the frame, forming a fender or shield against the working parts of the machine, and a loose sheet or canvas, R, connected with the upper end of this shield M, and with the outer swinging end of the elevator, serves to prevent any grain from escaping in its passage from one to the other. Sufficient slack is provided in this apron R to permit the free movement of the binders' carriage relative to the apron, and also the adjustment of the pivotal frame H as desired.

Parts of the machine not particularly described may be made in any usual or preferred manner.

Having thus described my invention, what I claim as new, and desire to secure by Letters Patent, is—

1. The stripper-belts F², in combination with the platform-apron D and elevator D', substantially as described.

2. The reversible elevator-apron D', in combination with the elevator-bottom C² and the yielding retaining-rods *i*, for adapting said apron to elevate the grain upon either its upper or lower face, as described.

3. The reversible auxiliary stripping-belts *g*, working on rollers mounted in a frame, H, pivoted to the upper end of the elevator-frame, in combination with the reversible elevator-apron, arranged and operating substantially as and for the purpose specified.

4. The pivoted grain-receptacle E, in combination with the slotted elevator-bottom C², as described.

In testimony whereof I have hereunto set my hand this 9th day of January, A. D. 1874.

JOHN H. ELWARD.
